UNITED STATES PATENT OFFICE

HEINRICH KUGLER, OF ZURICH, SWITZERLAND, ASSIGNOR TO JOHANN KESSLER AND
GEORGE FISCHER, BOTH OF ZURICH, SWITZERLAND

MATCHMAKING MACHINE

Application filed June 13, 1929. Serial No. 370,613, and in Germany June 22, 1928.

The present invention has reference to improvements in match-making machinery and relates more specifically to a device for inserting the splints into the perforated dipping bars.

Devices for inserting the splints into the perforated bars in match-making machines are known, in which the splints to be inserted are received from a hopper by a grooved plate 5 reciprocated for that purpose or by a stationary grooved plate along the grooves of which a tongued cross plate is displaced, which is further moved up and down to get into the range of the splints and afterwards out of 10 the range of the grooved plate. With the first mentioned construction the splints are inserted by the to and fro moving grooved plate itself and to permit this the grooves must be limited at the rear whereby the 15 grooves can only be cleaned with difficulty particularly at their rear end forming the pushing wall. With the second mentioned 20 type the cleaning of the grooves is rendered difficult owing to the grooved plate being stationary.

The device for inserting the splints according to the present invention is provided, besides with a to and fro moving grooved plate also with a vertically reciprocating 25 tongued cross bar taking part in the displacement movement of the grooved plate, the distance of the tongued cross bar from the front edge of the grooved plate being adjustable.

This combination of grooved plate and 30 tongued cross bar permits continuous grooves which may be kept clean over their total length by means of cleaning combs, whilst the adjustability of the tongued cross bar permits of readily adapting the device to handle 35 splints of different length.

A constructional example of the subject matter of the present invention is illustrated on the accompanying drawings, in which only 40 those parts of the match-making machine are illustrated which are necessary for the comprehension of the invention. In these drawings:

Fig. 1 is an elevation of the machine showing 45 the driving mechanism,

Fig. 2 shows in elevation details of the driving mechanism,

Fig. 3 is a plan view of Fig. 2 with parts shown in section,

Fig. 4 shows in an end elevation with parts 55 shown in section and on a larger scale further details of the driving mechanism,

Fig. 5 is a section along V—V in Fig. 4,

Fig. 6 shows in a vertical section the elements of the device for inserting the splints 60 in one operative position,

Fig. 7 is a section along VII—VII in Fig. 6,

Fig. 8 is part of a plan-view of the grooved plate,

Fig. 9 is a section corresponding to Fig. 6 65 but with the elements in a different working position,

Fig. 10 is a section corresponding to Fig. 6 with the tongued cross bar being in a different 70 adjusted position,

Fig. 11 shows part of the means for adjusting the cross bar, and

Fig. 12 shows part of a perforated dipping bar.

Referring now to Figs. 6-9 of the drawings 75 1 denotes the horizontal grooved plate provided with grooves 2 and 3 of different depth and serving for receiving the splints from the hopper 4. In the drawings only the splints A housed in the grooves 2 and 3 are 80 shown; in each of the grooves 2 one splint A is housed, whilst each of the grooves 3 contains three superimposed splints A of which the lowermost is inserted into the perforated 85 bars.

The grooved plate 1 is fixed to a carrier 5 and the latter is moved to and fro in the direction of the grooves by the following means illustrated in Figs. 1-3. The carrier 5 is at both ends fixed to a block 6 adapted to slide in a horizontal guide 7. The reciprocating movement of the block 6 is obtained from a shaft 8 to which an eccentric 9 is fixed and the rod 10 of the eccentric is linked at 11 to the block 6. The shaft 8 is driven by a spur gearing 12 from the main driving shaft 13 of the machine. From the shaft 8 the step by step movement of the perforated bars 14 along the guides 15 and past the device for inserting the splints is obtained by the inter- 90 95 100

mediary of a bevel gear drive 16, a shaft 17, a worm 18 on the latter, a pin wheel 19 co-operating with said worm and gear wheels 20 cooperating with the ends of the perforated bars.

5 To the carrier 5 a rail 21 is secured by means of screws 22 of which only one is shown and the tongued cross bar 23 which pushes the splints into the perforated bars 14 bears against the rail 21. The tongued cross bar 23 is adapted to carry out an up and down movement and takes part in the horizontal reciprocating movement of the grooved plate 1. To this end the cross bar 23 is connected to 15 a vertical arm 24 at each end carrying at its upper end two rollers 25 running along a horizontal groove 26 (Fig. 5) of a slide 27 adapted to move up and down in a vertical guide 28 provided in the frame 29 of the machine. The head 27 is reciprocated in the vertical direction by means of a two-armed lever 30, rod 31, link 32, bell crank lever 33 having a roller 34 cooperating with a groove 35 of a cam disk 36 (Figs. 1 and 4).
 20 25 The tongued cross bar 23 having teeth or tongues 37 corresponding to the grooves 2 and 3 of the plate 1 is guided on the rail 21 by means of set screws 38 and slots 39 of which only one is shown in Figs. 6 and 7. The grooved plate 1 is provided with a longitudinal slot 40 to permit the tongued cross bar 23 to pass through the plate 1 and over the forward edge of which the ends of the splints project for engagement by the tongues of said bar.

40 In order to insert the splints the tongued cross bar 23 is first moved from its position shown in Fig. 6 in the upward direction so that its teeth 37 act upon the splints A when the plate 1 together with the bar 23 moves forward. Simultaneously with the tongued bar 23 a rear part 41 of the wall of the hopper 4 is moved upward to permit the forward movement of the splints A. To this end the part 41 is connected by means of arms 42 to the slide 27, i. e. to the same member which causes the upward movement of the cross bar 23. The movable part 41 of the wall is designed at its lower edge as a comb 43 and is partly covered on the inner side of the hopper 4 by a covering strip 44 which prevents the splints from being jammed in between the part 41 and the plate 1 when the former moves in the downward direction. The hopper 4 is further provided with a tongued bar 45 for guiding the splints A on being inserted into the dipping bars 14.
 45 50 55

50 During the rearward movement of the grooved plate 1 subsequent to the insertion of the splints the cross bar 23 and the rear part 41 of the hopper wall are simultaneously lowered. Thereby the cross bar 23 moves out of the slot 40 of the grooved plate 1 and the teeth 43 of the wall part 41 engage the grooves

2 and 3 of the plate 1 for cleaning these grooves.

As is shown in Fig. 10 a plate 46 is interposed between the rail 21 and the carrier 5 and is provided with a slot 47 for the passage 70 of the screw 22 and with a handle 48. The interposition of the plate 46 causes the tongued cross bar 23 to be brought nearer to the front edge of the grooved plate 1 by the thickness of the plate 46, so that it is adjusted 75 to insert shorter splints.

Plates 46 of different thickness may be provided which may be interposed as required. Instead of plates 46 other means may be provided for adjusting the tongued cross bar 23 80 without having to remove the latter from its rail 21.

49 denotes a part of the front wall of the hopper hinged to the remaining part to form a flap. The latter is provided at its lower edge with teeth 50 cooperating with the grooves 2 and 3 of the grooved plate 1 and it may be lifted about its hinge joint 52 for inspecting the grooved plate 1. During the working the flap 49 is locked in its closed position by means of a latch 53, so that the teeth 50 effect a cleaning action on the grooved plate 1 during the forward and backward movement of the latter. This arrangement is of advantage, in that the flap is readily accessible, can be raised to remove or straighten crossed splints and remove imperfect splints and slivers without removing all the splints in the magazine to remedy improper feed of the splints, due to such causes.

100 I claim:

1. In a device for inserting splints into dipping bars of a match-making machine, in combination, a hopper for holding the splints, a grooved plate for receiving splints to be inserted from the hopper, a tongued cross bar cooperating with said groove plate for inserting the splints from said grooves into the bars, means for imparting a to and fro movement in the direction of the grooves to said grooved plate, means for connecting said tongued cross bar to said groove plate to cause the former to take part in the movement of the latter, means to impart an upward and downward movement to said tongued cross bar to move it into and out of contact with the splints, and means to alter the distance between said tongued cross bar and the front edge of said grooved plate for adapting the device to deal with splints of different lengths.

110 115 120 125 130 2. In a device for inserting splints into dipping bars of a match-making machine, in combination, a hopper for holding the splints, a grooved plate for receiving splints to be inserted from the hopper, a tongued cross bar cooperating with said groove plate for inserting the splints from said grooves into the bars, means for imparting a to and fro movement in the direction of the grooves to said

- grooved plate, means for connecting said tongued cross bar to said grooved plate to cause the former to take part in the movement of the latter, means to impart an upward and downward movement to said tongued cross bar to move it into and out of contact with the splints, means to alter the distance between said tongued cross bar and the front edge of said grooved plate for adapting the device to deal with splints of different lengths, a tongued member formed by a portion of a wall of the hopper and adapted to cooperate with the grooves of said grooved plate for cleaning purposes, and means for imparting an up and downward movement to said tongued cleaning member. 70
3. In a device for inserting splints into dipping bars of a match-making machine, in combination, a hopper for holding the splints, a grooved plate for receiving splints to be inserted from the hopper, a tongued cross bar cooperating with said groove plate for inserting the splints from said groove into the bars, means for imparting a to and fro movement in the direction of the grooves to said grooved plate, means for connecting said tongued cross bar to said grooved plate to cause the former to take part in the movement of the latter, means to impart an upward and downward movement to said tongued cross bar to move it into and out of contact with the splints, means to alter the distance between said tongued cross bar and the front edge of said grooved plate for adapting the device to deal with splints of different lengths, a tongued member formed by a portion of a wall of the hopper and adapted to cooperate with the grooves of said grooved plate for cleaning purposes, means for imparting an up and downward movement to said tongued cleaning member, and a further cleaning member cooperating with said grooved plate and being formed by a hinged part of a wall of the hopper. 80
4. In a device for inserting splints into dipping bars of a match-making machine, in combination, a hopper for holding the splints, a grooved plate for receiving splints to be inserted from the hopper, a tongued cross bar cooperating with said groove plate for inserting the splints from said groove into the bars, means for imparting a to and fro movement in the direction of the grooves to said grooved plate, means for connecting said tongued cross bar to said grooved plate to cause the former to take part in the movement of the latter, means to impart an upward and downward movement to said tongued cross bar to move it into and out of contact with the splints, means to alter the distance between said tongued cross bar and the front edge of said grooved plate for adapting the device to deal with splints of different lengths, a tongued member formed by a portion of a wall of the hopper and
- adapted to cooperate with the grooves of said grooved plate for cleaning purposes, and a rigid connection between said tongued member and said means for imparting an upward and downward movement to said tongued cross bar to cause the latter and said tongued member to move in unison. 85
5. In a device for inserting match splints into dipping bars of match making machines, the combination with a transversely reciprocated and longitudinally slotted grooved plate for receiving the splints to overhang the forward edge of the slot, of a vertically movable tongued cross bar connected with said plate to move into the slot for engagement with the ends of the splints, and means to adjust the cross bar to and from the front edge of the slot for operating on different lengths of splints. 90
6. In a device for inserting match splints into dipping bars of match machines, the combination with a hopper, a grooved plate therebelow to receive the splints in the groove; of a hinged flap on the rear wall of the hopper which, when opened by the operator will enable him to remove or straighten crossed splints and slivers. 95
7. In a device for inserting match splints into dipping bars of match machines, the combination with a hopper, and a grooved plate therebelow to receive the splints in the groove; of a hinged flap on the rear wall of the hopper which, when opened by the operator will enable him to remove or straighten crossed splints and slivers, said flap having cleaning teeth on its lower edge for entering said groove. 100
8. In a device for inserting match splints into dipping bars of match machines, the combination with a hopper and a grooved plate therebelow to receive the splints in the groove; of a hinged flap on the rear wall of the hopper which, when opened by the operator, will permit him to remove or straighten crossed splints and slivers, said flap having cleaning teeth on its lower edge for entering said groove, and latching means to hold the flap closed. 105
